SPOON

Christy M. Del Mas, New York, N. Y., assignor to Michael P. Grace, New York, N. Y.

Application December 12, 1952, Serial No. 22,684

Term of patent 14 years

(Cl. D44—29)

Fig. 1.

Fig. 2.

To all whom it may concern:

Be it known that I, Christy M. Del Mas, a citizen of the United States of America, residing at city, county, and State of New York, have invented a new, original, and ornamental Design for a Spoon, of which the following is a specification, reference being had to the accompanying drawing, forming part thereof.

Fig. 1 is a top plan view of a spoon, showing my new design;

Fig. 2 is a fragmentary cross section taken on line 2—2 of Fig. 1; and

Fig. 3 is a fragmentary cross section taken on line 3—3 of Fig. 1.

I claim:

The ornamental design for a spoon, as shown.
